HYDRAULIC STROKE REGULATOR FOR PUMPS

Arthur L. Ellis, New Rochelle, N. Y., assignor to The Waterbury Tool Company, Waterbury, Conn., a Corporation of Connecticut

Application July 17, 1931. Serial No. 551,386

3 Claims. (Cl. 103—38)

The invention relates to hydraulic transmissions of the type which include a hydraulic pump, and has for its object to provide a novel and efficient controlling mechanism whereby the operation of said pump may be automatically controlled to bring about predetermined regulations as to speed and direction of operation in the mechanism of which the pump forms a part. Other more specific objects will appear from the 10 description hereinafter and the features of novelty will be pointed out in the claims.

In the accompanying drawings, which illustrate several examples of the invention without defining its limits, Fig. 1 is a diagrammatic view 15 of one form of the novel arrangement; Fig. 2 is a detail side elevation thereof, with parts in section, on an enlarged scale; Fig. 3 is a corresponding view of a check valve forming part thereof; Fig. 4 is a detail sectional view showing a shuttle valve and a by-pass relief valve which constitute part of the invention; Fig. 5 is a fragmentary elevation showing another arrangement of the novel features; Fig. 6 is a diagrammatic view thereof; Fig. 7 is a detail 20 view of a four-way valve included in the arrangement, and Fig. 8 is an elevation partly in section of a preferred form of hydraulic pump comprising part of the construction.

For the purpose of illustration and description the invention is shown in the drawings as embodied in a machine tool of the planer type, it being understood that the illustrated example does not define the limits of the invention, and that is intended to exemplify the general type 35 of machine tools for which the novel mechanism is specially designed.

In the drawings 15 represents the reciprocating table of a machine tool of the planer type, arranged to be reciprocated by hydraulic 40 means, constituting a hydraulic motor which in the illustrated example is shown in the form of a cylinder 16 and co-operating elements; in the instant arrangement the table 15 is carried by the cylinder 16, the latter being slidably mounted upon a stationary piston which divides said cylinder 16 into independent, opposite end chambers in any customary manner. The aforesaid piston is fixed in place by means 45 of piston rods 20 and 21 which project in opposite directions beyond the cylinder 16 and are secured in members 22 projecting upwardly from a base 23 constituting part of the frame or support of a machine tool of the conventional planer type. The piston rods 20 and 21 are hollow and are provided respectively with axial

channels having no communication with each other and terminating at the outer ends of the piston rods 20 and 21, said channels being connected with the operating mechanism as will be pointed out more fully hereinafter. The 60 planer or its equivalent as exemplified by the table 15 may include any and all features commonly found in such tools, and said planer has been shown only in a fragmentary way because per se it forms no part of the invention. 65

The channel of the piston rod 20 is connected with a pipe 28 which leads to the chamber 29 of a shuttle valve 30, said chamber 29, in turn, being connected by means of a pipe 31 with one side of a hydraulic pump 32; the channel of the 70 piston rod 21 is connected by means of a pipe 33 and branch pipe 33a with a second chamber 29a of said shuttle valve 30, said chamber 29a being in turn connected, by means of a pipe 34, with the other side of said hydraulic pump 32. In the 75 preferred construction a back pressure valve of suitable form, is located at a convenient point between the shuttle valve 30 and the channel of the piston rod 21 in communication with the pipe 33 and branch pipe 33a; in addition, a by-pass 80 valve 36, the specific construction of which will be fully described later on, is connected with the pipes 31 and 34 so as to establish communication therebetween under the conditions and in a manner which will appear more fully hereinafter. 85

As shown in Fig. 4 communication between the chambers 29 and 29a of the shuttle valve 30 is controlled by valves 37 and 37a and co-operating valve seats 38 and 38a formed at opposite ends of a cage 39 located interiorly of said valve 30 and constituting an interior passage connecting the two chambers 29 and 29a thereof. The valves 37 and 37a are both mounted upon a common valve stem 40 so as to constitute a duplex valve movable as a unit, as clearly illustrated in Fig. 4. 95 In order to prevent any chattering in the shuttle valve 30, and to avoid difficulties due to misalignment, plungers 41 are connected by means of links 42 with the opposite ends of the valve stem 40 or in other words with the valves 37 and 37a respectively. The plungers 41 are slidably mounted in cylinders or recesses 43 formed in the opposite end members 44 of the shuttle valve 30 and connected by means of passages 45 with the interiors of the chambers 29 and 29a respectively; the plungers 41 partake of the movements of the valves 37 and 37a, and with the cylinders 43 constitute dash pots as will be readily understood. The interior passage in the casing of the 100 shuttle valve 30 is connected by means of a pipe 105

110

46 with a conventional expansion box or other storage of oil; as the expansion box or equivalent storage of oil per se forms no part of the instant invention and is well known it has not been deemed necessary to show the same in the drawings.

The by-pass valve 36, as also illustrated in Fig. 4, comprises a relief valve 47 preferably provided with a peripheral lip 48 for assisting said valve to open and to remain open, and co-operating with a valve seat 49 formed at one end of a cage 50 secured in the valve casing preferably so as to be removable therefrom. The valve 47 is maintained upon and returned to the seat 49 by means of a spring 51, one end of which bears against a member 52 provided with a projection 53 in engagement with said valve 47; the member 52 is carried by a plunger 54 slidably mounted in a sleeve 55 having an annular flange 56 at its one end against which the other end of said spring 51 abuts. The plunger 54 and sleeve 55, in addition to their other functions, constitute means for guiding the member 52 in its movements, said sleeve 55 being adjustable by means of an adjusting screw 57 to vary the tension of the spring 51; the adjusting screw 57 is fixed against unintentional movement for instance, by means of a lock nut 58; to further guard against interference with the screw 57 a protecting cover 57a may be screwed into the valve casing to completely enclose said screw 57. To steady the valve 47 in its movements and to prevent chattering thereof, the one end of the cage 50 is formed as a cylinder 59 which communicates with the interior of the casing of the valve 36 and slidably accommodates a plunger 60 connected by means of a stem 61 with the valve 47; the plunger 60 and cylinder 59 together constitute a dash-pot as clearly shown in Fig. 4.

The hydraulic pump 32 may be of any suitable form and as shown is of the well known Waterbury type which consists of a casing or housing in which a rotatable cylinder barrel 86 is mounted upon a driving shaft 87. As illustrated in Fig. 8 the barrel 86 includes a plurality of cylinders 88 each having a port 89 arranged to communicate in periodic succession with suction and pressure ports with which said pump is provided in the well known way and which control the communication between said cylinders 88 and the pipes 31 and 34. Pistons 90 are slidably mounted in the cylinders 88 and are connected by piston rods 91 with a swash plate 92 rotatably supported in a tilting box 93 which is connected with the driving shaft 87 by means of a universal joint 94 in the conventional manner. The tilting box 93 and swash plate 92 are adjustable to different angular positions relatively to the shaft 87 to vary the output of the pump and the direction of flow whereby the speed and direction of operation may be selectively changed, as will be pointed out more fully hereinafter. The pump 32 itself may be operated in any conventional manner, as by means of an electric motor 94 connected with the driving shaft 84 of said pump 32 for instance as shown in Fig. 1.

For the purpose of adjusting the position of the swash plate 92 and tilting box 93 of the hydraulic pump 32, the tilting box 93 is provided with a stub shaft 95 which fits into a rocking bearing 96 provided in a control shaft 97; the latter is vertically guided in suitable guideways 98 provided in the casing of the pump 32 as illustrated in Fig. 8. In order to facilitate the adjustment of the swash plate 92 and tilting box 93,

the actuation of the control shaft 97 is preferably effected by means of a servo-motor 99, which, in the illustrated example, is mounted directly upon the casing of the hydraulic pump 32, as illustrated in Fig. 8. The servo-motor 99 may be of any conventional type, and as shown in the drawings, comprises an upright cylinder in which a piston 100 is slidably mounted and connected with one end of the control shaft 97; the latter projects into the cylinder of the servo-motor and is slidably guided in an adapter 101. The piston 100 divides the servo motor cylinder into independent upper and lower chambers 102 and 103 respectively, and itself is formed with longitudinal conduits 104 and 105, the first of which opens to the upper chamber 102, while the second leads to the lower chamber 103. The conduits 104 and 105 are connected by means of lateral branches with opposite end portions of a valve chamber 106 formed by a central bore in the piston 100, as illustrated in Fig. 3.

On its outer face, the piston 100 is cut away or reduced between its ends to form an annular passageway 107 between itself and the cylinder of the servo-motor 99, as best shown in Fig. 8; this annular passageway 107 is connected by means of a radial channel 108 with the valve chamber 106 approximately at the middle point of the latter. A sleeve 109 is connected with and projects upwardly from the piston 100 through a suitable stuffing box 110 forming part of or secured to the cylinder of the servo-motor, the arrangement being such that said sleeve 109 partakes of the vertical movement of the piston 100. A valve stem 111 extends downwardly through the axial bore 112 of the sleeve 109 and at its lower end carries a pilot valve 113 slidably mounted in the valve chamber 106. The pilot valve 113 is reduced at its central portion to provide relatively enlarged end portions of heads 114 and 115 at its opposite ends, which end portions slidably fit the valve chamber 106 in a fluid tight manner; in addition, the pilot valve 113 is provided with one or more longitudinally extending conduits 113a which establish communication between the opposite end portions of the valve chamber 106.

Fluid under pressure for operating the servo-motor 99 is supplied by a low pressure pump 116, which may be driven from the driving shaft 84 of the pump 32 by means of a sprocket chain or belt drive 117, as shown in Fig. 1. The pump 116 has its intake side connected by means of a branch pipe 118 and a pipe 119 with the casing of the hydraulic pump 32 and has its outlet side connected by means of a branch pipe 120 and pipes 121 and 122 with a check valve 123, which in turn, is connected by means of a pipe 124 with the annular passageway 107 of the servo-motor 99, the arrangement being such that in a certain position of the check valve 123, as will be more fully explained hereinafter, low pressure oil from the pump 116 will be supplied to said annular passageway 107 when the load on the servo-motor 99 is small. As clearly shown in Fig. 3, the communication between the pipes 122 and 124 is controlled by means of a valve 125 located in a chamber 126 of the check valve 123, said valve 125 being carried by a stem 126 and being maintained upon and returned to its seat by a relatively light spring 128. The chamber 126 is connected by means of channels 129 with additional chambers 130 and 131 respectively, said chambers 130 and 131 in turn being connected by pipes 132 and 133 with the high pressure side of the valve plate of 150

the hydraulic pump 32, as shown in Fig. 1. The communication between the chamber 130 and the pipe 132 and between the chamber 131 and 133 is controlled respectively by check valves 134 and 135 carried by stems 136 and individually under the influence of springs 137, as shown in Fig. 3. With this arrangement, as will appear more fully hereinafter, when the oil pressure increases and thus causes an increased load on the servo-motor 99, high pressure oil is available from the high pressure side of the pump 32 for the operation of said servo-motor.

The valve stem 111 of the servo-motor 99 is connected with an arm 138 provided with a stop 139 extending between laterally spaced shoulders 140 and 141 comprising parts of a stop bracket 142 carried by the sleeve 109, as shown in Fig. 1; the arm 138 is carried by a vertically movable member 143 slidably mounted in a bearing bracket 144 fixed upon the casing of the servo-motor 99 and provided at its lower end with a roller 145. The roller 145 is arranged in rolling engagement with a cam slide 146 and is maintained in rolling contact therewith by means of springs 147 connected at one end to projections 148 mounted on the arm 138, while the other ends of said springs are secured to projections 149 located upon the bearing bracket 144.

As shown in Fig. 2, the cam slide 146 comprises a lower horizontal section *a* and an intermediate recess or horizontal section *b* and an upper horizontal section *c*, the sections *a* and *b* being connected by an inclined section *d* and the sections *b* and *c* being connected by an inclined section *e*; the arrangement is such that the cam slide is of substantially step-like form in which the horizontal sections *a*, *b* and *c* are located at progressively high levels. The cam slide 146 is slidably mounted in a suitable stationary horizontal guide 150 supported, for instance, upon the casing of the hydraulic pump 32. For the purpose of adjustably and automatically determining the extent of the sliding movements of the cam slide 146 in opposite directions, said cam slide is connected with a screw threaded rod 151 forming a continuation of a slideable member or plunger 152 slidably mounted in a stationary bearing 153 and including at its free end a screw-threaded extension 154. An externally threaded collar 155 is threaded upon the rod 151 and a corresponding collar 156 is threaded upon the extension 154, said collars 155 and 156 constituting stops adapted to engage the opposite ends of the bearing 153 to thereby arrest the sliding movements of the cam slide 146 in opposite directions. Obviously, by shifting the collars 155 and 156 on the rod 151 and extension 154 respectively, the extent of the reciprocating movement of the cam slide 146 may be selectively adjusted; any suitable means such as a set screw 157 or a lock nut 158 may be utilized for fixing collars 155 and 156 in their adjusted positions. For operating the cam slide 146, the latter is connected by means of a piston rod 159 with a piston 160 capable of being reciprocated in a cylinder 161 carried by supporting means 162 suitably mounted, for instance, upon the casing of the hydraulic pump 32, as shown in Fig. 2. The opposite ends of the cylinder 161 are independently connected by means of pipes 163 and 164 with a four-way valve 165 which in turn is connected by means of a pipe 166 with the previously mentioned pipe 119 leading to the casing of the hydraulic pump 32 and by means of a pipe 167 with

the previously mentioned pipe 121 and branch pipe 118 leading to the low pressure pump 116.

As shown in Fig. 7, the pipe 163 leads to a chamber 168 forming part of the valve 165, while the pipe 164 leads to a chamber 169 therein; the pipes 166 and 167 are connected respectively with chambers 170 and 171 of the valve 165, communication between said chambers and consequently between the various pipes being controlled by slide valves 172 and 173 slidably mounted in the casing of the valve 165 and carried by a valve rod 174 projecting exteriorly of the casing and terminating in a forked member 175 adapted for connection with a suitable operating member such as a foot treadle which has been omitted from the disclosure. As shown in Figs. 1 and 2, a stud 176 projects downwardly from the cam slide 146 and is engaged by the opposed free ends of piston rods 177 and 178, which rods are slidably mounted in stuffing boxes 179 located at one end of cylinders 180 and 181 respectively; the rods 177 and 178 are connected with pistons 182 and 183 which are slidably mounted in the respective cylinders 180 and 181. Pipes 184 and 185 lead from the outer ends of the respective cylinders 180 and 181 and are connected with the previously mentioned branch pipe 120, which leads to the low pressure pump 116. The inner end of the cylinder 180 is connected by means of a pipe 186 with a pipe 164, while a similar pipe 187 connects the inner end of the cylinder 181 with the pipe 163. The pipe 185 preferably is also connected by means of a pipe 188 with a relief valve 189 from which a pipe 190 leads to the casing of the hydraulic pump 32, as shown in Fig. 1.

In practice, during operative periods of the machine in which the novel features are embodied, the hydraulic pump 32 will be continuously operated by the motor 94 to rotate the barrel 86 and with it the swash plate 92 and tilting box 93 with their associated elements. With the parts illustrated in the neutral position in Fig. 8, in which the swash plate 92 and tilting box 93 extend transversely at right angles to the driving shaft 87, no oil will be pumped by the pump 32 and the mechanism will accordingly remain stationary. When, however, the tilting box 93 and swash plate 92 are adjusted to inclined positions in diagonal relation to the aforesaid driving shaft 87 in the manner to be more fully set forth hereinafter, the pistons 90 will be reciprocated in the cylinders 88 and accordingly will pump oil or its equivalent through the pipes 31 and 34. Under such conditions, with the tilting box 93 and swash plate 92 inclined in one direction, oil from the one side of the pump 32 passes through the by-pass relief valve 36 and shuttle valve 30, and through the pipe 28 into the bore of the piston rod 20 and from thence through suitable outlet ports into the one end chamber of the cylinder 16. The oil pressure thus created in said chamber will, by reacting against the aforesaid stationary piston, be exerted upon the right hand end of the cylinder 16 and accordingly will move said cylinder, and with it the reciprocating table 15 toward the right in Fig. 1, for instance, at a relatively slow speed. At the same time, the oil in the other end chamber of the cylinder 16 will be forced through suitable ports and the bore of the piston 21 into and through the pipe 33, by which it is carried down to the back pressure valve 35. The oil pressure in the latter, at this stage, will operate said valve in a manner to cause the oil or its equivalent to pass

to the branch pipe 33a. With this arrangement, the action of the back pressure valve 35 serves to maintain a slight back pressure on the return side and thereby prevents jumping of the cylinder and the planer table or its equivalent and steadies the travel of the latter in one direction. As at this stage more oil is being pumped into the one chamber than is passing out of the other cylinder chamber, due to differences in dimensions of these chambers, the high pressure oil in the pipe 28 will be effective in the chamber 29 of the shuttle valve 30 to close the valve 37 thereof, and to open the co-operating valve 37a whereby the chamber 29a of said shuttle valve is brought into communication with the pipe 46 and the source of oil with which it communicates. With the parts in this position, a supply of oil accordingly passes from the oil expansion box or other supply through the pipe 46 into the chamber 29a of such shuttle valve, which is in communication with the pipe 34 leading to the pump 32, so that the deficiency in the amount of oil required for the cylinder chamber of larger dimensions is properly supplied. To cause the cylinder 16 and table 15 to be moved on a return stroke to the left in Fig. 1, the tilting box 93 of the pump 32 is adjusted to a reversed inclined position from that previously occupied, so that oil under pressure now passes through the pipe 34, chamber 29a of the shuttle valve 30, branch pipe 33a into the check valve 35. The pressure thus created operates said check valve 35 to permit the oil to pass through the pipe 33 to the bore of the piston 21. From thence the oil passes into the other cylinder chamber and by reacting upon the stationary piston within said cylinder and acting upon the left hand end of the cylinder 16 moves the latter, and with it the table 15 toward the left in Fig. 1. Because of the relative difference in area of such other chamber, this return movement of the cylinder 16 and table 15 may, for instance, be at a relatively high speed, so as to bring about a quick return of the parts mentioned. During this operation, a relatively larger volume of oil may have to be displaced from the chamber at the right hand end of the cylinder 16, which is taken care of in the following manner: The oil from the cylinder chamber in question passes through the bore of the piston 20 and is conducted therefrom by the pipe 28 to the chamber 29 of the shuttle valve 30. During this operation, the valve 37a is closed, and the co-operating valve 37 is opened, so that the chamber 29 is in communication with the pipe 46 whereby the excess oil is conducted to the oil reservoir or equivalent supply.

In order to take care of any excessive overloads, which may develop in the system, for instance in case the planer table 15 or its equivalent 60 should stall against either one or the other end of the machine, the by-pass valve 36 is provided, said valve in effect constituting a relief valve which functions when the pressure has built up to a predetermined amount, in a condition for 65 instance as set forth above. Under such conditions oil from the pump will pass through the pipe 34 into this valve 36 and by moving the valve 47 from its seat will flow through said by-pass valve 36 to the pipe 31 and back to the pump 32. 70 It will be noted that the valve 47 is controlled by the dash-pot arrangement 59—60 which not only prevents chattering of this valve, but also serves to properly guide the same in its operative movements. In addition, the valve 47 includes a 75 peripheral lip 48 which assists in the opening

of said valve and in maintaining it in an open position against the tension of the spring 51. The dash pots 41—43 of the shuttle valve 30 likewise serve to prevent chattering of the valves 37 and 37a, which in many instances is severe enough to pound the valves to pieces. The flexible connections 42 between the valves 37 and 37a respectively, and the plunger 41 of the aforesaid dash pots avoids any difficulties which otherwise might arise because of misalignment, and makes it unnecessary to provide extreme exactness in the axial registry of these parts.

The mechanism so far described is controlled by means of the servo-motor 99 and associated elements, which will now be described.

Oil for the operation of the servo-motor piston 100 is supplied by the low pressure pump 116 through the branch pipe 120, pipes 121, 122 to the check valve 123 and acts upon the valve 125 therein to permit said oil to flow into the chamber 126 and through the pipe 124 to the annular passageway 107 of said servo-motor. Under certain conditions to be more fully referred to hereinafter, oil for the operation of said servo-motor may also be taken from the high pressure side of the pump 32 through the pipes 132 and 133, which conduct said oil to the check valve 123 and by raising the valves 134 and 135 permit said oil to pass into the chambers 130 and 131, and channels 129 to the pipe 124 and to the aforesaid annular passageway 107. With this arrangement, it is possible to use low pressure oil from the pump 116 when the load on the servo-motor 99 is small, and when the oil pressure increases 100 and causes a greater load on the servo-motor to utilize higher pressure oil from the high pressure side of the pump itself. With the parts located as shown in Fig. 1, the control mechanism is in a neutral position, in which the roller 145 rests on the section or in the recess b of the cam slide 146. The setting of the cam slide 146, which controls the operation of the servo-motor 99 and consequently the adjustment of the hydraulic pump 32, is determined by operating the four-way valve 165, the valve rod 174 of which 105

may be manually operated by any suitable means generally in the form of a foot pedal suitably connected to the forked member 175. By adjusting the valve 172 from the neutral position shown in Fig. 7 toward the left, pressure oil from the pipe 167 will pass through the chambers 171 and 172 to the pipe 163, and to the left hand end of the cylinder 161. The piston 160, and with it the stem 159 and cam slide 146, is thus moved to the right in Figs. 1 and 2 until the adjustable nut 155 engages the one end of the bearing 153. As this shifting of the cam slide 146 takes place, the roller 145 will ride up on the inclined section e to an extent determined by the position of the nut 155 on the stem 151. The member 143 will be correspondingly raised and will lift the arm 138, and bring about a corresponding upward movement of the valve stem 111 and accordingly raises the pilot valve 114 in the valve chamber 106, so that the conduit 105 is brought into communication with the radial channel 108 and consequently with the annular passageway 107. At this stage, oil under pressure will accordingly pass to the chamber 103 beneath the piston 100 and will lift the same to correspondingly raise the control shaft 97 and to thereby adjust the tilting box 93 and swash plate 92 to an angular inclination with respect to the driving shaft 87. Unless the arm 138 is raised extremely fast, the servo-motor piston 100 and the pilot valve 113 will 110

move almost in unison so that the stop 139 will not engage the shoulder 140; if however the arm 138 is lifted at an excessive speed the stop 139 will contact with the shoulder 140 and thereby 5 will prevent the pilot valve 113 from striking against the end of the sleeve 109 in this direction of movement. The feeding or equivalent speed of the table 15 will thus be determined by the angular setting of the swash plate 92. This speed 10 obviously may be varied by shifting the nut 155 on the stem 151 to permit the roller 145 to travel along the inclined section *e* to a greater or lesser extent, the greatest speed being attained when the travel of said roller 145 is such that it reaches 15 the highest horizontal section *c* of the cam slide 146. Similarly, by shifting the valve rod 174 to the right in Fig. 7 a sufficient distance to establish communication between the pipes 167 and 164 through the chambers 171 and 169 of the 20 four-way valve 165, oil under pressure will be introduced to the right hand end of the cylinder 161 through the pipe 164. This will cause the piston 160 to be moved to the left in Fig. 1 and will correspondingly adjust the cam slide 146 25 until the adjustable collar 156 engages the opposite end of the bearing 153. During these movements, the roller 145 will travel downwardly along the inclined section *d* to the horizontal section *a* 30 or to an intermediate point on said section *d* dependent upon the position of the collar 156 on the extension 154. As this happens, the member 143 and arm 138 will be correspondingly moved downwardly and will correspondingly shift the pilot valve 113 downwardly in the valve chamber 35 106. If the downward movement of the arm 138 is extremely fast the stop 139 will engage the shoulder 141 and thus will prevent the pilot valve 113 from contacting with the end of the control shaft 97; otherwise the servo-motor piston 40 100 and the pilot valve 113 will move almost in unison in this direction also and the aforesaid contact will not take place. The downward adjustment of the pilot valve 113 will bring the conduit 104 into communication with the radial 45 channel 108 and accordingly will permit oil under pressure to pass into the chamber 102 above the piston 100. The latter will therefore be moved in a downward direction and will correspondingly adjust the control shaft 97 to adjust the swash 50 plate 92 and tilting box 93 to an oppositely inclined position relatively to the driving shaft 87. This adjustment of the parts will cause the table 15 or its equivalent to be operated in a return 55 movement. It will be understood that the vertical movements of the piston 100 in the casing of the servo-motor 99 continues with each setting of the pilot valve 113 until the inner ends of the lateral branches of the conduits 104 and 105 overtake and register with the heads 114 and 115 of the pilot valve 113. From this it will be clear that the extent to which the pilot valve 113 is shifted in the valve chamber 106 will determine the extent of movement of the piston 100 and accordingly 60 will predetermine the degree of adjustment of the tilting box 93 and swash plate 92 in one direction or the other relatively to the driving shaft 87.

As the aforesaid upward movement of the piston 100 takes place, the pressure fluid in the chamber 102 above said piston will flow downwardly, through the conduit 104 to the lower end of the valve chamber 106 from which said fluid passes through a channel 97a, extending lengthwise of the control shaft 97, to the interior of the casing of the pump 32. Similarly as the piston

100 moves downwardly, the pressure fluid in the chamber 103 beneath said piston, will be forced up through the conduit 105 to the upper end of the valve chamber 106; from this point said fluid flows downwardly through the channels 113a of the pilot valve 113 and through the aforesaid channel 97a to the interior of the casing of the pump 32.

If at any time during the operation set forth above, the oil pressure increases, for instance, when actual work is being performed by the table 15 or its equivalent, and thus correspondingly increases the load on the servo-motor, this pressure will become effective through the pipe 124 upon the valve 125 of the check valve 123 and will seat said valve; at the same time, the high pressure oil in either the pipe 132 or 133 will become effective to raise one or the other of the valves 134 or 135, and consequently will permit a supply of oil at relatively higher pressure to reach the servo-motor through the pipe 124 and to operate the same in the intended manner. Which one of the valves 134 or 135 is operated under these conditions will be determined by the direction in which the servo-motor piston 100 is being actuated at the time.

For the purpose of automatically restoring the cam slide 146 to the neutral position shown in Fig. 1, and for maintaining it therein, the centering cylinders 180 and 181, and their associated elements, are provided. The arrangement is such that pressure oil is introduced into both cylinders 180 and 181 behind the pistons 182, 183 thereof, and to thereby cause the rods 177 and 178 of said pistons to act upon the stud 176, 110 which projects downwardly from the cam slide 146; with this arrangement, the cam 146 is definitely returned to and maintained in the neutral position in which the control mechanism is inoperative.

As so far described, the operation of the machine provides, for instance, for an adjustable slow speed cutting or other operative stroke, and an adjustable high speed return stroke and for positive centralization in the neutral position. 120 In practice, it has been found that in some instances the cutting or other operative stroke consists in part of what might be termed an "ineffective initial stroke" and a continuing "effective stroke", under which conditions it becomes desirable to have part of said stroke operate at a relatively higher speed in order to bring the parts to the actual operative position as quickly as possible.

An example of an arrangement whereby these 125 results may be accomplished is shown in Figs. 5 and 6. As illustrated in these figures the machine, in the main, is the same as that previously described and operates in approximately the same way. Instead of the adjustable nut 155 and 130 collar 156 and the co-operating fixed stops represented by the opposite end of the bearing 153 included in the machine first described, an adjustable stop 155a in the form of a headed bolt is 135 screwthreaded into and is fixed in its adjusted position, for instance, by means of a bracket 153a mounted upon the cylinder 161, and lock nut 155b. The stop 155a is located in the path of the cam slide 146 and is directly engaged thereby when said cam slide 146 is moved toward the 140 left in Figs. 5 and 6, in a return stroke. On the feeding or other operative stroke, in which the piston 160, and with it the piston rod 159 and cam slide 146, moves toward the right in Figs. 145 5 and 6, said cam slide 146 engages an adjustable 150

stop 156a. The latter consists of a rod slidably mounted in the stuffing box 153b of a stationary cylinder 153c suitably supported in the machine, said stop rod 156a being connected with a piston 152a slidably mounted in said cylinder 153c as shown in Fig. 5. The piston 152a is hollow and is arranged to reciprocate relatively to a head 152b located interiorly of said piston, and carried by a rod 152c which projects through an opening 152d formed in the removable end member 152e of said piston 152a as illustrated in Fig. 5. The rod 152c is adjustable lengthwise of the cylinder 153c to vary the position of said head 152b which constitutes a stop to limit the movement of the piston 152a toward the left in Fig. 5, as will appear more fully hereinafter; for this purpose the rod 152c is in threaded engagement with the removable member 153d of the cylinder 153c and is fixed in an adjusted position, for instance, by lock nuts 153e; to protect the latter against unintentional misadjustment, said nuts and the outer end of the rod 152c may normally be covered by a protecting cap 153f which is screwthreaded upon a boss projecting from the member 153d as shown in Fig. 5. The cylinder 153c is provided at its opposite ends with ports 191 and 192 respectively, from the first of which a pipe 193 leads to the pipe 119, which connects with the branch pipe 118 of the pump 116 and with the casing of the pump 32, so that said pipe 193 may be said to be always open to the exhaust; the second port 192 is connected by means of a pipe 194 which leads to the casing of a control valve 195 as illustrated in Fig. 6. The valve 195 corresponds in construction and operation with the valve 165 with the exception that the one port of the valve 195 which corresponds to the port of the valve 165 in communication with the pipe 163 is plugged or otherwise closed, or is omitted entirely. The valve 195 is further connected by means of pipes 196 and 197 with the pipes 166 and 176, which in turn lead to the pipes 119 and 121 respectively, and accordingly place the chambers of the valve 195 which correspond to the chambers 170 and 171 of the valve 165, in communication with the hydraulic pump 32 and the pump 116, as illustrated diagrammatically in Fig. 6. The internal construction of the valve 195 includes slide valves similar to the slide valves 172 and 173 of the valve 165 and similarly adjustable by means of a valve rod 174a provided at its free end with a forked member 175a adapted for connection with a suitable operating member such as a foot treadle as in the case of the valve 165.

With the arrangement shown in Figs. 5 and 6, and assuming that the piston 152a occupies the extreme left hand position shown in said figures, the cam slide 146 will be shiftable to the right only to a slight extent until arrested by engagement with the stop rod 156a. This will cause only a slight upward travel of the roller 145 on the section e of the cam slide 146 and thus will bring about an operation of the servo-motor 99 which produces only a slight angular displacement of the tilting box 93 and swash plate 92 of the hydraulic pump 32; as a result, the operation of the parts will be such the table 15 will develop an operative movement at relatively slow speed. The left hand position of the stop rod 156a and the speed of the operative movement of the parts may be varied by adjusting the nuts 153e on the rod 152c, this will correspondingly shift the head 152b which arrests the movement of the piston 152a to the left and thus determines

the left hand position of the stop rod 156a and the extent of right hand movement of the cam slide 146.

When it is desired to operate the table 15 or its equivalent at a maximum speed the valve rod 174a is shifted to operate the valve 195 in such a manner that the pipe line 194 is brought into communication with the pipe 196 and pipes 166 and 119, and accordingly is open to the exhaust. This releases the pressure in the cylinder 153c which is effective on the right hand end of the piston 152a therein. This will allow the pressure exerted on the piston 160 toward the right and the resulting movement of the cam slide 146 to shift the stop rod 156a to the right until the piston 152a is arrested at the right hand end of the cylinder 153c in Figs. 5 and 6. The cam slide 146 will under such conditions be capable of moving to the right in Fig. 5. to a maximum extent before being arrested by the stop rod 156a with the result that the roller 145 will travel upward on the section e of the cam slide to the top thereof. The servo-motor 99 will consequently be operated in a manner to bring about a greater angular displacement of the tilting box 93 and swash plate 92 and the output of the pump 32 will be increased so that in the illustrated example the speed of operation of the table 15 correspondingly increased.

As previously stated, by shifting the location of the head 152b through the medium of the rod 152c and nuts 153e the point at which the movement of the piston 152a toward the left in Fig. 5 is arrested by the stop rod 156a, may be varied. It will be understood that the piston 152a is moved toward the left and maintained in its final left hand position by pressure fluid passing into the cylinder 153c through the port 192 from the pipe 194 as a result of a proper manipulation of the valve 195. With the aforesaid arrangement the cam slide 146 will be pushed to the right in Figs. 5 and 6 until it engages the stop rod 156a and may be held in this adjustment as long as desired by the operator, after which said cam slide 146 may be permitted to shift to a full right position by the operation of the valve 195 as set forth. The cam slide 146 may be returned toward the left to an intermediate position by suitably manipulating the valve 195 to introduce pressure fluid to the right hand end of the cylinder 153c through the pipe 194. It is thus possible to provide for an intermediate speed between zero and the maximum speed obtainable when the roller 145 reaches the top of the cam slide 146.

In the illustrated examples so far described, the table 15 is operated by a plunger type hydraulic motor indicated by the cylinder 16, piston 17 and associated elements. It will be understood that the operation of the table 15 may be accomplished by means of a conventional hydraulic motor of the rotating type and arranged to drive the table through a suitable set of spur gears and a rack as is usual, for instance, in planer construction, said motor being connected with the pump 32 in the usual way. In such installations, the back pressure valve 35 and the shuttle valve 30 may be omitted as the high speed return may be secured directly through the control of the hydraulic pump 32.

The novel features, when embodied in reciprocating machine tools such as planers, milling machines and the like provide definite and specialized control for such machines and bring about operations of maximum efficiency. With

the arrangements set forth the speed of operation of the machine tool may be varied and adjusted to efficiently meet the requirements of any type of work within the operative range of the machine.

Various changes in the specific forms shown and described may be made within the scope of the claims without departing from the spirit of the invention.

10 I claim:

1. Controlling mechanism for a variable flow, reversible pump comprising a servo-motor for adjusting said pump to vary the operation thereof, setting mechanism for controlling the operation of said servo-motor, a reciprocating cam slide for variably actuating said setting mechanism, a pressure actuated piston whereby said cam slide is operated, an adjustable stop for engaging said cam slide to arrest its movements in one direction, and a pressure actuated adjustable stop for engaging said cam slide to arrest its movements in the opposite direction.

2. Controlling mechanism for a variable flow, reversible pump comprising a servo-motor for adjusting said pump to vary the operation thereof, setting mechanism for controlling the operation of said servo-motor, a reciprocating cam slide for variably actuating said setting mechanism, a pressure actuated piston whereby said cam slide is operated, an adjustable stop for engaging said

cam slide to arrest its movements in one direction, a cylinder connected with a source of pressure, a piston movable in said cylinder, a stop rod connected with said piston and constituting an adjustable stop for engaging said cam slide to arrest its movements in the opposite direction, and adjustable means whereby the movements of said piston and stop rod in one direction are arrested.

3. Controlling mechanism for a variable flow, reversible pump comprising a servo-motor for adjusting said pump to vary the operation thereof, setting mechanism for controlling the operation of said servo-motor, a reciprocating cam slide for variably actuating said setting mechanism, a pressure actuated piston whereby said cam slide is operated, an adjustable stop for engaging said cam slide to arrest its movements in one direction, a stationary cylinder connected with a source of pressure, a hollow piston slidable in said cylinder, a stop rod connected with said piston and constituting an adjustable stop for engaging said cam slide to arrest its movements in the opposite direction, a head located within said piston for determining the extent of movement of the piston and stop rod in one direction, and an adjustable rod carrying said head for selectively varying the position of the latter.
